CAR COUPLER

William J. Metzger, Euclid, Ohio, assignor to National Malleable and Steel Castings Company, Cleveland, Ohio, a corporation of Ohio

Application November 15, 1941, Serial No. 419,329

21 Claims.

(Cl. 213—146)

This invention relates to car couplers, and more particularly pertains to anticreep means for the lock and to an improved lock operating and knuckle throwing mechanism.

The invention is concerned with the types of railway car couplers having a pivoted knuckle and a vertically movable lock for holding the knuckle in closed position. In this type of coupler it is very important that means be provided to prevent undesired upward creeping of the lock such as would result in unlocking of the knuckle. It is an object of the invention to provide a positive anticreep for the lock of rugged construction which may be easily released by the lock operating mechanism when it is desired to raise the lock for uncoupling cars.

My improved anticreep means is simple in construction and has a substantial overlap with one of the parts of the coupler which may be renewed when the anticreep lug becomes worn so as to restore the anticreep means to its original condition. My improved anticreep comprises a pivoted member on the bottom of the lock which underlies a lug on the knuckle tail and which is withdrawn from anticreep position by the same means that raises the lock. The anticreep means may readily be seen from the front of the coupler so that a simple inspection thereof will determine whether or not it is functioning properly.

A further object of my invention is the provision of novel operating means for raising the lock and for throwing the knuckle, one of the features of which is a direct contact between the rotor lever mounted on the bottom of the coupler and the bottom of the lock for forcing or jolting the lock from its initial seated position. A further feature of the lock operating means is the provision of a positive lockset position of the lock on the knuckle thrower. My improved lock operating means also provides for increased power for throwing the knuckle due to an improved toggle action between the lock and lifter link and due to the direct engagement of the lifter link with the knuckle thrower near the end of the knuckle throwing movement.

A still further feature of the invention lies in the positioning of the rotor lever so as to prevent it from being hit by flying objects and thus eliminate accidental uncoupling by this means. Other objects and advantages of the invention will be clear from the following description taken in conjunction with the drawings, in which:

Figure 1 is a longitudinal sectional view through a coupler embodying my invention, showing the parts in locked position,

Figure 2 is a partial view in longitudinal section, showing the initial engagement of the rotor lever with the bottom of the lock, and showing the anticreep disengaged.

5 Figure 3 is a partial view in longitudinal section, showing the lifting force transferred from the rotor lever to the lifter link, a portion of the lock being broken away.

Figure 4 is a partial view in longitudinal section, with the lock in lockset position.

Figure 5 is a partial view in longitudinal section, showing engagement between the lock and knuckle thrower at the start of knuckle throw.

15 Figure 6 is a view similar to Fig. 5, with the parts moved until the lifter link engages the knuckle thrower.

Figure 7 is a view similar to Fig. 5, showing the parts at the end of knuckle throw.

Figure 8 is a horizontal sectional view showing 20 the parts in locked position.

Figure 9 is a view similar to Fig. 8, showing engagement between the leg of lock and knuckle thrower at the start of knuckle throw.

25 Figure 10 is a view similar to Fig. 8, with the knuckle partially open and showing engagement between the lifter link and the knuckle thrower.

Figure 11 is a view similar to Fig. 8, showing the knuckle fully thrown.

Figure 12 is a transverse vertical sectional view, 30 taken generally along line 12—12 of Fig. 1.

Figure 13 is a partial view in longitudinal section, showing the lock moved upwardly until the anticreep is in engagement, part of the lock being broken away; and

35 Figure 14 is an enlarged fragmentary view showing the same relation of parts as Fig. 13.

Referring to the drawings, the head 10 of the coupler has a pivoted knuckle 11 having a tail 12 and a locking face 13. Projecting laterally 40 from the knuckle tail at the bottom of the locking face is a projection 14. The lock 15, when the parts are in locked position, engages locking face 13 of the knuckle and a wall 16 at the opposite side of the lock cavity to prevent pivotal movement of the knuckle. The lock has a leg 17 extending downwardly into an opening 18 in the bottom of the coupler and is formed with a laterally projecting trunnion 19. Pivotal mounted 45 on trunnion 19 is a lifter link 20 having a portion 21 projecting above the trunnion and normally underlying projection 14 on the knuckle tail. Extending downwardly from the trunnion, link 20 has a portion 22 formed with a slot 23. A rotor lever 24 is pivotally mounted on the 50 coupler head rearwardly of the lock on trunnions

25 and has a slotted arm 26 which receives portion 22 of the lifter link. A rivet 27 passing through slot 23 pivotally joins arm 26 with the bottom of link 20. An eye 28 is formed on each side of lever 24 to receive an operating rod 29 (Fig. 12) for rotating the lever and raising the lock, as will be hereinafter described.

Referring to Figs. 1-11 inclusive, the successive steps in the movement of the lock from locked position to knuckle thrown position will be described. Projecting laterally from arm 26 of rotor lever 24 is a lug 30 which upon rotary movement of the lever is adapted to engage undersurface 31 of the lock. By this direct engagement, or by a few successive blows if necessary 10 to disengage the lock, the latter is moved upwardly as the rotor lever is pivoted. Upon movement of the lever 24 from the position shown in Fig. 1 to that shown in Fig. 2, the pivot point between the lever and link 20, which is the rivet 27, is moved forwardly and upwardly, causing the rivet to move forwardly and upwardly in slot 23 and forcing arm 22 of link 20 forwardly. At the same time upper portion 21 of link 20 is moved rearwardly and withdrawn from beneath projection 15 14 on the knuckle tail. As rotary movement of lever 24 progresses the lock moves upwardly faster than lug 30 and the lifting force is transferred to rivet 27 (Fig. 3) and link 20 which being pivoted to the lock on trunnion 19 raises the lock upwardly. It will be observed that slot 23 is formed of two angularly disposed parts. The lower portion of the slot slopes slightly forwardly and upwardly and the upper portion slopes upwardly and rearwardly. As rivet 27 moves upwardly in the lower portion of the slot very little movement of link 22 takes place. Hence, the upper end of the link moves only a small amount from beneath projection 14. However, after the rivet reaches the junction of the two portions it 20 will slide in the upper portion and very rapidly withdraw the remainder of arm 21 from beneath projection 14. Thus the slight amount of jiggling of lever 24 that takes place as the car moves over the track will not affect link 22 to such an extent as would withdraw arm 21 from beneath the anticreep projection on the knuckle.

In Fig. 4 the lock is shown in lockset position with the shoulder 32 on the rear side thereof resting on arm 33 of the knuckle thrower 34. It will be observed that as the lock moves into lockset position the force thereon exerted by the rotor lever through link 20 is directed rearwardly and upwardly, thus the bottom of the lock is moved rearwardly toward arm 33 of the knuckle thrower and a positive lockset is assured. In the view shown the parts are at rest, with rivet 27 engaging the lower end of slot 23 in link 20.

Figures 5 and 9 show the position of the parts at the beginning of knuckle throw. The initial movement of the knuckle thrower is caused by the lock, through the engagement of leg 17 thereof with the end of arm 33 at point 35. The lever arm from point 35 to the center of trunnion 36 on the knuckle thrower, which is the pivot point thereof, is substantially the maximum that can be obtained. As the knuckle thrower is rotated by the lock, arm 37 of the thrower acts upon surface 38 of the knuckle and rotates the latter about its pivot 39. In a position of the parts intermediate those shown in Figs. 5 and 9, and 6 and 10, both the lock leg and link 20 are in engagement with arm 33 of the knuckle thrower. By the time the parts have reached the position shown in Figs. 6 and 10, only link 20 is in

engagement with arm 33. During the remainder of the knuckle throwing movement force is transmitted from the rotor lever through link 20 directly to the knuckle thrower. The transition from the lock leg to the link is gradual and thus a smooth knuckle throwing movement is obtained. Surface 40 on the link slopes away from the side of arm 33 of the thrower so that only the outer end of surface 40 engages the arm and thus the force of the link against the thrower acts at substantially the greatest moment arm from trunnion 36. Although the engagement of surface 40 with arm 33 reduces the lever arm for rotating the knuckle, lever 24 has been rotated to such a position that the force from the lever through link 20 to arm 33 is very close to being in the same direction as the movement of arm 33. This direct action therefore compensates for the reduction in length of the lever arm. Figs. 7 and 11 show the position of the parts at the end of knuckle throw at which time the force is still exerted on the knuckle thrower by link 20. It will be observed that after the arm 33 has moved away from the lock leg, as shown in Figs. 6 and 7, the lock has no further function in the knuckle throwing movement.

In Fig. 13 the lock is shown moved upwardly until the upper end 21 of link 20 is in engagement with projection 14 on the knuckle tail, which constitutes an anticreep lug. Further undesired movement of the lock upwardly is thus effectively prevented and the knuckle remains securely locked. There is a substantial overlap between the engaging surfaces on link 20 and projection 14, as will be observed from Figs. 12 and 13. Moreover, since the bottom portion of leg 17 of the lock is confined against substantial longitudinal movement by walls 41 and 42 of the coupler head, the slight amount of movement of the lock longitudinally of the coupler will have little or no effect on the amount of overlap between the anticreep surfaces.

Surface 43 on the under side of projection 14 has a radius of curvature r (Fig. 14) shorter than the length of arm 21 of link 20. Also, the engaging surface 44 at the end of arm 21 is formed with a radius slightly less than that of surface 43 to assure a good contact with surface 43. If, therefore, with surfaces 43 and 44 in engagement as shown in Figs. 13 and 14, rotor lever 24 should be accidentally struck while the train is in motion and moved upwardly so as to tend to rotate the upper end 21 of link 20 from beneath projection 14, the lock would first have to be pulled downwardly due to the camming action of surface 43 against surface 44. This feature of my invention is illustrated in Fig. 14 in which arc a is drawn through the outermost point on arm 21 about the center 45 of trunnion 19. It will be apparent, therefore, that portion 46 of abutment 14 which is below arc a , will preclude withdrawal of arm 21 from beneath the abutment. Before arm 21 can pivot rearwardly from the position shown, lock 15 must move downwardly an amount sufficient to permit end surface 44 to clear portion 46 of the abutment. Downward movement of the lock, however, must proceed against the pressure of the knuckle tail which is sufficient to cause arm 21 to remain in its anticreep position. Also, in the event that the lock should accidentally creep upward with the arm withdrawn part way from beneath projection 14, any further withdrawal must be accompanied by downward movement of the lock against the pressure of the knuckle tail as aforementioned and is therefore precluded.

Moreover, the slight amount of vibration of the knuckle and lock that takes place as the train is moving and the camming action of surfaces 43 and 44 will cause the link to move back to the position illustrated in Figs. 13 and 14. The placing of surfaces 43 and 44 forwardly of the pivot point 45 of link 20 as shown, has the effect of increasing the amount of abutment 14 which lies below arc *a* and therefore increases the camming action between those surfaces.

In Fig. 1 the carrier iron for the coupler is shown in dot-dash lines. It will be observed that rotor lever 24 has been pivoted on the coupler as high as is practical and as a result no part of it extends below the carrier iron. The rotor lever then is protected by the carrier iron against flying objects that may be thrown forwardly and upwardly from the track or the under side of the car.

While I have illustrated the invention in connection with what is known as a wedge lock in which the locking surfaces on the lock and knuckle are tapered, it will be understood that the invention can be used with a lock and knuckle having vertically engaging surfaces, without departing from the spirit of the invention.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. A car coupler having a knuckle, a vertically movable lock for said knuckle, operating means for raising said lock to unlock said knuckle, and means shiftable by said operating means adapted in one position to engage said knuckle to limit undesired upward movement of said lock and in another position to allow upward movement of said lock.

2. A car coupler having a knuckle and a vertically movable lock, a lever pivoted on said coupler to the rear of said lock, a link pivotally joining said lever and lock, means on said link adapted to engage said knuckle to limit upward movement of said lock when said link is in one position, and means comprising said lever for moving said link to a position allowing upward movement of said lock.

3. A car coupler having a knuckle and a vertically movable lock, a lever pivoted on said coupler to the rear of said lock, a link pivoted to said lock and slidably joined to said lever, said knuckle having a portion adapted to overlie the upper end of said link when said lock is in locked position to limit upward movement of said lock, and said lever being adapted to pivot said link and move the upper end thereof from beneath said portion of the knuckle to allow upward movement of said lock.

4. In a car coupler a knuckle, a vertically movable lock having a downwardly extending leg, a rotor lever pivoted to said coupler, said lever having a portion normally spaced from said leg adapted to be pivoted into engagement with said leg to effect upward movement of said lock, and means operatively connecting said lock and lever adapted to raise said lock after a predetermined amount of direct raising thereof by said lever upon further rotation of the latter.

5. In a car coupler a knuckle, a vertically mov-

able lock having a downwardly extending leg, a rotor lever pivoted to said coupler, and a link operatively connecting said lock and lever, said lever having a portion normally spaced from said leg, said link and lever being constructed and arranged so that upon actuation of said lever to effect uncoupling said portion engages said lock to raise the latter a predetermined amount after which further raising of said lock is effected by the action of said link against said lock.

6. In a car coupler a knuckle, a vertically movable lock having a downwardly extending leg, a rotor lever pivoted to said coupler having a pair of spaced arms, and a link extending between said arms, said link being operatively connected to said arms and to said lock, one of said arms having a portion normally spaced from said leg which upon actuation of said lever is adapted to engage the under side of said leg to effect initial raising of said lock after which further raising thereof is effected by the action of said link against said lock.

7. In a car coupler a knuckle, a vertically movable lock having a downwardly extending leg, a rotor lever pivoted to said coupler, a link operatively connecting said lock and lever, means on said lever normally spaced from said leg adapted to engage said leg upon actuation of said lever to raise said lock, said link being adapted to cooperate with said lock and lever so that after a predetermined amount of raising of said lock directly by said lever further raising thereof is effected through said link.

8. In a car coupler a knuckle, a vertically movable and rearwardly swingable lock having a depending leg, a knuckle thrower pivoted intermediate its ends and adapted to rotate in a horizontal plane, a rotor lever pivoted to said coupler, and a link operatively joining said lock and lever, said link being adapted to move said lock leg into engagement with one end of said thrower to move the latter toward knuckle thrown position, said link after a predetermined amount of movement of said thrower being adapted to move into knuckle throwing engagement with said thrower to pivot the latter to full knuckle thrown position.

9. In a car coupler a knuckle, a vertically movable and rearwardly swingable lock having a downwardly extending leg, a knuckle thrower pivoted for movement in a horizontal plane and having a laterally extending arm, a rotor lever pivoted to said coupler, a link positioned adjacent said leg and operatively connecting said lock and lever, said link being adapted to move said leg into engagement with the outer end of said arm to rotate said thrower toward knuckle thrown position, said link after a predetermined amount of movement of said thrower being adapted to engage said arm directly to pivot said thrower to full knuckle thrown position.

10. In a car coupler a knuckle, a vertically movable and rearwardly swingable lock having a downwardly extending leg, a knuckle thrower pivoted for movement in a horizontal plane, said thrower having an arm extending from the pivot point thereof and positioned rearwardly of said lock, a rotor lever pivoted to said coupler, and a link operatively joining said lock and lever, said link being positioned adjacent said leg and pivotally connected thereto, said link being adapted to move said leg into engagement with the outer end of said arm to pivot said thrower toward knuckle thrown position and after a predetermined amount of movement of said thrower,

being adapted to engage said arm directly to complete the knuckle throwing operation.

11. In a car coupler a knuckle having a tail, a vertically movable lock, a rotor lever pivoted to said coupler, and a link operatively connecting said lock and lever, the upper end of said link underlying said tail to limit upward movement of said lock when the latter is in locked position.

12. In a car coupler a knuckle having a tail, a vertically movable lock, a rotor lever pivoted to said coupler, and a link operatively connecting said lock and lever, said link being pivotally connected intermediate the ends thereof to said lock, one end of said link underlying said tail to limit upward movement of said lock when the latter is in locked position.

13. In a car coupler a knuckle having a tail, a vertically movable lock, a rotor lever pivoted to said coupler, and a link operatively connecting said lock and lever, means on said link underlying said tail to limit upward movement of said lock when the latter is in locked position.

14. In a car coupler a knuckle having a tail, a vertically movable and rearwardly swingable lock, a knuckle thrower pivoted for movement in a horizontal plane having a laterally extending arm, a rotor lever pivoted to said coupler, a link operatively connecting said lock and lever, means on said link underlying said tail to limit upward movement of said lock when the latter is in locked position, and means on said link adapted to move into engagement with said arm to actuate said thrower to open said knuckle.

15. In a car coupler a knuckle having a tail, a vertically movable lock, a rotor lever pivoted to said coupler, and a link pivotally connected to said lock and lever, the upper end of said link underlying a portion of said tail and adapted to engage the under side thereof to limit upward creeping of said lock when the latter is in locked position, the end surface of said link and the under surface of said tail portion being curved in such a manner that upon engagement therebetween said lock must move downwardly a predetermined amount before said end of said link can pivot from beneath said tail portion.

16. In a car coupler a knuckle having a tail, a vertically movable lock having a downwardly extending leg, a rotor lever pivoted to said coupler, a link pivoted to said lock and lever, said link having an upwardly extending arm underlying a portion of said tail when said lock is in locked position and adapted to engage the under side thereof to limit upward movement of said lock, the under surface of said tail portion being so shaped that the rearmost point of contact between said link and surface is a shorter distance from the pivot point of said lever than points on said surface forwardly of said point of contact, and the end surface of said arm having substantially the same curvature as said under surface.

17. In a car coupler a knuckle having a tail, a vertically movable lock having a downwardly extending leg, a rotor lever pivoted to said

coupler, a link operatively connecting said lock and lever, said link having an arm underlying a portion of said tail when said lock is in locked position to limit upward movement of the latter, said link being pivotally connected to said lock leg and having a pin and slot connection with said lever, said latter connection being adapted to pivot said link to withdraw said arm from beneath said tail during uncoupling, said slot being so shaped that during a predetermined amount of initial pivoting of said lever to effect uncoupling said arm remains in anticreep relation to said tail.

18. In a car coupler having a knuckle, a vertically movable lock having a downwardly extending leg, a rotor lever pivoted to said coupler, a link pivoted intermediate its ends to said leg, the upper end of said link underlying a portion of said tail when said lock is in locked position to limit upward creeping of the latter, the lower end of said link having a slot, and a pin in said slot joining said link and lever and adapted to pivot said link upon rotation of said lever, said pin normally being positioned at the lower end of said slot when said coupler is locked, the lower portion of said slot being shaped to follow substantially the path of travel of said pin during a predetermined amount of initial rotation of said lever so that said upper end of said link remains in anticreep relation to said tail.

19. In a car coupler having a knuckle, a vertically movable lock having a downwardly extending leg, a rotor lever pivoted to said coupler, a link pivoted intermediate its ends to said leg, the upper end of said link underlying a portion of said tail when said lock is in locked position to limit upward creeping of the latter, the lower end of said link having a slot, and a pin in said slot joining said link and lever and adapted to pivot said link upon rotation of said lever, said pin normally being positioned at the lower end of said slot when said coupler is locked, said slot having a lower portion sloping substantially in the direction of the path of travel of said pin during a predetermined amount of initial rotation of said lever and an upper portion sloping in a direction opposite to the direction of travel of said pin so that when the latter slides in said upper portion said upper end of said link is withdrawn from beneath said tail.

20. A knuckle for a car coupler having a locking face, a lug projecting laterally from said locking face adapted to be engaged by the lock operating means of the lock engaging said face when the parts are assembled in a coupler to limit undesired upward movement of the lock.

21. A knuckle for a car coupler having a locking face, a lug projecting laterally from said face beneath a lock when said parts are assembled in a coupler, said lug being adapted to be engaged by a movable member on a lock operating mechanism to limit upward movement of the lock when said member is in a position beneath said lug.

WILLIAM J. METZGER.
